ROTATABLE CLOSURE STRUCTURE HAVING
YIELDABLE LOCKING MEANS

Chester A. Brooks, Mission, Kans.

Application May 7, 1945, Serial No. 592,377

2 Claims. (Cl. 222—513)

1

This invention relates to closures of the permanently fixed type and has for its primary aim to provide lids or covers for receptacles that may be moved to and from an open position without separating the same from the mouth of the receptacle.

One of the important objects of this invention is to provide a closure structure for containers that is specially mounted to permit rotation and that cooperates with a part on the container as rotary motion is imparted thereto, to the end that the container is effectively sealed when the closure is in one position, is open when the closure is in another position, and friction is reduced to a minimum as the closure and container are relatively shifted to establish the said open and closed conditions.

This invention has for further aims and objects the provision of closure structure for containers wherein is included a cam groove on the container neck, pins on the closure for engagement with the cam groove, and a sufficiently thick and resilient cushion between the closure and container for cooperating with the cam and pins as the structure is manipulated.

Other objects of the invention will appear during the course of the following specification, referring to the accompanying drawing, wherein:

Fig. 1 is a central sectional view through a closure structure made to embody the present invention.

Fig. 2 is a sectional view taken on line II—II of Fig. 1.

Fig. 3 is a sectional view through a closure structure made to embody a modified form of the invention; and

Fig. 4 is a stretch out of the cam groove forming neck of the closure illustrated in Fig. 1.

Much effort has been expended in producing a closure structure that will maintain the closure in assembled relation with the container with which it is associated, yet allow relative movement between the closure and container for the purpose of selectively opening and closing the container for removing the contents of the latter. Objectionable costs, complicated mechanism, and devices usually out of order constitute, in the main, results of effort heretofore expended.

This invention aims to provide a closure structure that will be inexpensive, effective and positively acting through the exertion of a minimum amount of effort.

The form of the invention shown in Figs. 1

2

and 2 is particularly useful with collapsible tubes of conventional character and comprising a body 10 terminating in a neck 12, the latter being of somewhat more rigid construction than the material from which body 10 is made.

Neck 12 is closed at its mouth by a wall 14 through which outlet opening or port 16 is provided for the passage of material that may be stored in body 10. The outer annular periphery of neck 12 has a serpentine groove 18 therein, the depth whereof is sufficient to receive the inner ends of a pair of pins 20. These pins are carried by the skirt portion 22 of a cap 24 and are urged against the upper wall of groove 18 by the inherent resiliency of the gasket 26 disposed between wall 14 of neck 12 and the inner face of the top of cap 24. This gasket 26 has sufficient strength to maintain its full thickness, to the end that the space between wall 14 and the inner side of cap 24 is completely filled when pins 20 snap into notches 28. These notches are in communication with groove 18 and are disposed a distance apart equal to the spacing of pins 20. In the illustrated embodiment of the invention, both pins 20 and notches 28 are in diametrically opposed relation, and the curvature of groove 18 is such as to have its portion between notches 28 curved upwardly toward the outer end of neck 12.

Openings 30 and 32 in gasket 26 and cap 24 respectively, are of substantially the same cross sectional area as opening 16 in neck 12, and when pins 20 are in the position shown in Fig. 1, openings 16, 30 and 32 are all in register to open the container.

As cap 24 is rotated, pins 20 ride in groove 18 and friction upon the sealing gasket 26 is eliminated by a movement of cap 24 away from the end of neck 12. Cap 24 is moved against the neck when it has been rotated through 180°, whereupon opening 16 will be closed by gasket 26 and the body 10 sealed against the escape of material therefrom.

In the form of the invention illustrated in Fig. 3, neck 50 is internally threaded to engage the threads of an ordinary fruit jar 52, which may be converted into a more handy container as the result of applying the closure structure thereto.

Neck 50 has a groove 54 formed therein which is of substantially the same contour as above described with respect to groove 18 and detents 56 are positioned as illustrated in the stretch-out of Fig. 4.

Cap 58 has a depending annular skirt 60 provided with diametrically opposed pins 62 and

these pins ride in groove 54 as cap 58 is rotated. An opening or port 64 formed through the top wall of neck 50 communicates with the interior of jar 52 and is aligned with openings 66 and 68 in a gasket 70 and cap 58 respectively, when the structure is manipulated to permit pouring of the contents of jar 52 through opening 64.

A coil spring 72 positioned at the axis of cap 58 rests in opposed sockets of cap 58 and neck 50 respectively, to prevent accidental displacement, and this spring maintains pins 62 against the upper edge of groove 54 and in notches 56 when cap 58 is fully opened or closed.

Gasket 70 is relatively thin and because of the size of the elements forming the structure illustrated in Fig. 3, is not relied upon to exert the force required to maintain pins 62 in detents or notches 56. Gasket 70 is rigidly attached to the underside of cap 58 and the same is true with respect to gasket 26, illustrated in Fig. 1.

Closure structure of the character described will remain assembled at all times, and accidental loss of the cap is thereby obviated. The manner of yieldably holding the caps in either of two stations results in a sufficiently positive lock without the necessity of separately manipulating such instrumentalities as have heretofore been employed in the nature of latches or set screws.

Pins 20 and 62 respectively are illustrated as having a pressed fit, but any means of securing the pins in place will be satisfactory, so long as they are secured against accidental removal.

Having thus described the invention, what is claimed as new and desired to be secured by Letters Patent is:

1. Closure structure for containers comprising a neck having a cylindrical side wall provided with an external, serpentine, continuous groove; notches in communication with the groove; a cap having a flat end wall and a cylindrical skirt, the latter being in circumscribing relation with the cylindrical wall of the neck, said cap and the neck having superimposed end walls; radial, inwardly-extending projections on the skirt and formed to enter the groove; resilient means between the superimposed end walls of the neck and cap; an outlet port formed in the end wall of the neck;

and an opening formed in the end wall of the cap, said opening and port each being eccentrically positioned for registry when the projections of the cap are in the notches respectively, said resilient means comprising a spring interposed between said end walls of the cap and the neck respectively.

2. Closure structure for containers comprising a neck having a cylindrical side wall provided with an external, serpentine, continuous groove; a plurality of equally-spaced notches in communication with the groove; a cap having a flat end wall and a cylindrical skirt, the latter being in circumscribing relation with the cylindrical wall of the neck, said cap and the neck having superimposed end walls; radial, inwardly-extending projections on the skirt and formed to enter the groove; resilient means between the superimposed end walls of the neck and cap; an outlet port formed in the end wall of the neck; and an opening formed in the end wall of the cap, said opening and port each being eccentrically positioned for registry when the projections of the cap are in the notches respectively, said groove being curved toward the resilient means along two diametrically-opposed portions thereof and away from said resilient means along two diametrically-opposed segments thereof, said notches each communicating with a corresponding segment of the groove at that edge thereof proximal to the resilient means and at the point thereon of greatest distance from said resilient means.
